(57) **CLAIM**

The ornamental design for a bicycle seat storage device, as shown and described.

DESCRIPTION

FIG. 1 a bottom view of a bicycle seat storage device.

FIG. 2 is a top view of the bicycle seat storage device of FIG. 1.

FIG. 3 is a right side view of the bicycle seat storage device of FIG. 1.

FIG. 4 is a left side view of the bicycle seat storage device of FIG. 1.

FIG. 5 is a front view of the bicycle seat storage device of FIG. 1.

FIG. 6 is a rear view of the bicycle seat storage device of FIG. 1.

FIG. 7 is a perspective top view of the bicycle seat storage device of FIG. 1.

FIG. 8 is a perspective bottom view of the bicycle seat storage device of FIG. 1.

FIG. 9 a bottom view of a second embodiment of the bicycle seat storage device.

FIG. 10 is a top view of the bicycle seat storage device of FIG. 9.

FIG. 11 is a right side view of the bicycle seat storage device of FIG. 9.

FIG. 12 is a left side view of the bicycle seat storage device of FIG. 9.

FIG. 13 is a front view of the bicycle seat storage device of FIG. 9.

FIG. 14 is a rear view of the bicycle seat storage device of FIG. 9.

FIG. 15 is a perspective top view of the bicycle seat storage device of FIG. 9; and,

FIG. 16 is a perspective bottom view of the bicycle seat storage device of FIG. 9.
